CLAIM

The ornamental design for a diagnostic testing apparatus for automobiles, as shown and described.

DESCRIPTION

The patent or application file contains at least one drawing executed in color. Copies of this patent or patent application publication with color drawing(s) will be provided by the Office upon request and payment of the necessary fee.

1. Diagnostic testing apparatus for automobiles

1.1 is a rear view.

1.2 is a front perspective view.

1.3 is a top view.

1.4 is a front view.

1.5 is a bottom view.

1.6 is a side view.

1.7 is a side view.
